UNITED STATES PATENT OFFICE

2,280,004

ROTARY WHEEL TRENCHING MACHINE

Vincent S. Penote, Cleveland, and Albert R. Askue, Mentor, Ohio, assignors to The Cleveland Trencher Company, Cleveland, Ohio, a corporation of Ohio

Original application October 13, 1939, Serial No. 299,306. Divided and this application May 6, 1940, Serial No. 333,480

2 Claims. (Cl. 37—97)

This invention relates to an improved trench digging machine and is a division of our copending application for Letters Patent filed October 13, 1939, and assigned Serial No. 299,306. The present invention is particularly concerned with an improved digging mechanism for a trenching machine. This, therefore, is the general object of the present invention.

Another object of this invention is the provision of a trench digging machine which will be especially adapted for the digging of comparatively narrow trenches under restricted space conditions, as for instance, between the curb and sidewalk in cities, towns, villages where obstructions such as trees, telephone poles and the like make machine digging extremely difficult.

A further object of this invention is to provide a trench digging machine of the wheel type with an improved digging wheel and wheel driving and supporting mechanism.

A more specific object of this invention is to provide an improved digging wheel for a trench digging machine which will reduce the overall width of the structural sections of the wheel entering the trench during the digging operation and thereby enable the digging of relatively narrow trenches.

Other objects and advantages of this invention will become more apparent from the following description, reference being had to the accompanying drawings in which we have illustrated a preferred embodiment of the invention. The novel and essential characteristics of the invention will be summarized in the claims.

In the drawings, Fig. 1 is a side elevation of a trench digging machine constructed in accord with the present invention; Fig. 2 is a rear elevation of the machine illustrated in Fig. 1; Fig. 3 is a fragmentary transverse sectional view of the machine, the plane of the section being indicated by the lines 3—3 on Fig. 1; and Fig. 4 is a vertical section as indicated by the lines 4—4 on Fig. 1.

Referring now to the drawings, and particularly to Fig. 1, the trench digging machine with which the present invention has been illustrated preferably comprises a frame 10, supported by a pair of spaced tractor belts 11. Mounted on the forward end of the machine is a motor 12, and mounted at the rear end of the frame is an upwardly extending forwardly inclined guideway 14. A supplemental frame 15 to support a digging wheel is mounted for movement lengthwise of the guideway and extends rearwardly

therefrom. Suitable driving mechanism (not shown) but operatively connected with the motor is provided to actuate the tractor belts and propel the machine, as well as to raise and lower the supplemental frame 15 and digging wheel on the guideway 14. In Fig. 1 the supplemental frame and digging wheel is shown in full lines in a raised position, and is indicated by dotted lines in a lowered or digging position. A detailed description of such a trenching machine, together with the propelling and wheel raising and lowering mechanisms will be found by reference to our copending application heretofore referred to.

The supplemental frame 15 which supports the digging unit, comprises a pair of substantially longitudinally extending, spaced frame members 28 which are secured together at their opposite ends by suitable cross-frame members 29. At its forward end the frame 15 is pivotally connected, as at 17, to a carriage 18, which is slidably mounted for movement in the guideway 14. The carriage 18 is provided adjacent its upper and lower ends with rollers 19, arranged to engage trackways 20 secured to the guideway.

25 The supplemental frame, together with the digging unit carried thereby is raised and lowered in the guideway 14 to regulate the depth of cut to be made by the digging unit as well as to raise such unit clear of the ground to facilitate 30 the transportation of the machine from place to place. This may be accomplished by any type of mechanism desired. However, we prefer to use the mechanism shown, described and claimed in our copending application heretofore mentioned.

35 Briefly, such mechanism contemplates supporting the outer end of the supplemental frame 15 by a pair of cables 22. As illustrated, each of the cables have one end secured to the guideway 14, as indicated at 23. From the points 23 each cable 40 passes around respective sheaves 27 which are mounted on the carriage to respective sheaves 24. The sheaves 24 are pivotally attached to the rearward end of the frame 15. From the sheaves 24 each cable 22 passes forwardly as at 25 and is 45 secured to the upper portion of the carriage to which the inner end of the digging wheel frame is pivoted.

The raising and lowering of the supplemental frame 15, together with the digging unit or wheel 50 26, is accomplished by a single operating means. As shown in Fig. 4, a hydraulic cylinder 30 is secured to the frame 10 and extends upward in the guideway 14. Suitable conduits 31 lead from this cylinder to a hydraulic pump 33 which is driven by the motor 12 in any suitable manner.

A valve mechanism controlled by a lever 32 is interposed in the conduit 31 and controls the flow of fluid to and from the cylinder 30. The cylinder 30 is provided with a piston (not shown) but the plunger 34 of which extends upward through the cylinder and is secured to the upper end of the carriage 18.

The operation of the hydraulic lift mechanism above described, will move the supplemental frame 15 and the digging wheel from the full line position shown in Fig. 1 to the dotted line position therein indicated, or vice versa. It is to be noted that the rearmost or outer end of the supplemental frame 15, during the lowering movement, will move at a greater rate of speed than the forward or pivot end. Thus when the wheel reaches substantially the position shown in dotted lines, the frame 15 will be substantially horizontal. Indeed, the arrangement is such that for all practical purposes the frame 15 will be substantially horizontal during most digging depths.

The improved digging wheel, with which the present invention is particularly concerned, comprises a pair of rotatably mounted metal rings 40. As shown in Figs. 1 and 3, these rings are maintained in spaced relation to each other by a plurality of digging buckets 41. These buckets may comprise U-shaped metal plates, the ends of each which engage the periphery of the rings 40. The buckets are preferably formed and secured to the rings as illustrated, described and claimed in Patent No. 1,927,323 issued to Vincent S. Penote, September 19, 1933. Briefly, the buckets are secured in position on the rings 40 by bars 42 which are welded to the sides of the buckets and secured to the side of the rings by suitable bolts 43.

The digging wheel is mounted between the two channel members 28 which form the supplemental frame 15. As illustrated in Figs. 1, 2 and 3, the supplemental frame 15 adjacent its rearmost or right hand end, is provided with a transverse shaft 44 carrying a pair of flanged members or wheels 45 which engage the inner periphery of the rings 40 of the digging wheel. At the forward end of the supplemental frame 15, a shaft 43 supports a flanged member 47 which similarly engages the inner periphery of the wheel. The digging wheel rings 40 are maintained in contact with the flanged members 45 and 47 by a pair of flanged wheels 48 carried by struts 49 which are secured to the frame 15. Thus the flanged wheels 45, 47 and 48 are spaced in a triangular formation about the inner periphery of the digging wheel, maintaining it in position relative to the supplemental frame 15.

Also mounted on the supplemental frame 15 and extending transversely thereof and through the digging wheel is a conveyor 50 for ejecting the material which drops from the digging buckets during the digging operation. As shown in the drawings, this conveyor is supported by frame members 51 which are secured to frame members 28 of the supplemental frame 15. The conveyor comprises a flexible belt 52 which is looped around the pulleys or drums 53 rotatably journaled at opposite ends of the conveyor frame 51.

The material removed from the trench by buckets 41 is retained therein during the upward travel of the buckets (indicated by the arrow in Fig. 1) by a protecting plate 55. This plate is carried by the frame 15 and extends from the lower digging wheel supporting wheels 48 to a position substantially above the conveyor 50 and

bridges the gap between the two rings 40 which form the wheel. At its upper end the plate 55 is bent downwardly as indicated at 57 to guide the dug material from the buckets 41 onto the conveyor 50.

To insure ejection of the material from the digging buckets 41, a bucket cleaner is provided. This cleaner is best shown in Fig. 1, and comprises a bar 60 pivoted as at 61 to framework 59 and maintained in the position shown in Fig. 1 by a spring 62. The tension of this spring is such that under normal conditions the bar will be maintained in the position shown in Fig. 1, extending into the bucket, to cause material adhering thereto to be removed and fall onto the conveyor 50. If, however, any unforeseen obstruction, such as, for instance, a large piece of rock, may become wedged in a bucket, the ejector 60 may swing clockwise about its pivot (Fig. 1) and no damage will be done to either the ejector or any of the digging mechanisms.

The digging wheel is rotated by the motor 12. The motor 12 may be drivingly connected with the driven member of a differential gear mechanism unit, preferably through a suitable change-speed gear mechanism. For a detailed description of a preferred form of driving mechanism, reference may be had to our copending application, heretofore referred to. The differential driving unit is enclosed within a differential housing 70. The driving or cross shafts 71 of this unit extend outwardly at either end of the housing 70 and are each provided with a sprocket wheel 71'. The sprocket wheels 71' are connected by respective driving chains 72 with a pair of sprocket wheels 73 which are secured to opposite ends of the shaft 43 heretofore mentioned. The shaft is journalled in suitable bearings 74 mounted on the frame 15 as shown in Fig. 3.

The driving chains 72 are of such length as to facilitate the raising and lowering of the supplemental frame 15, together with the digging wheel. As shown in Fig. 1, each of these chains is maintained taut by a pair of idler sprockets 75 and 76. Each idler sprocket 75 engages its respective chain 72, as indicated in Fig. 1, and is rotatably supported by an axle 77 carried by the plunger 78, mounted in a housing 79. A suitable spring (not shown) but contained within the housing, acts to maintain the plunger and therefore the idler sprocket in its uppermost position. The other idler sprocket wheels, namely the sprocket wheels 76 ride on the top of the chain, as shown in Fig. 1. Each of these wheels are supported at one end of a lever 80, the other end of which is pivotally mounted on the axle 77 which carries its respective idler sprocket 75, heretofore described. Suitable springs (not shown) but preferably carried by respective axles 77 act to maintain their respective sprockets 76 in contact with the chains 72.

As heretofore mentioned, the digging wheel is driven from the shaft 43. As shown in the drawings, a pair of spaced driving gears 90 are drivingly secured to the shaft 43 and are arranged to mesh with the teeth 91 formed on the outer surfaces of the respective rings 40 of the digging wheel.

To facilitate the digging of a comparatively narrow trench the teeth 91 of the digging wheel comprise pins which are press fitted to the wheel, as shown in Fig. 3, and thereafter welded in position, thus maintaining the overall width of the wheel at a minimum.

The flanged member 47, heretofore mentioned as comprising one of the supports for the digging wheel, is rotatably mounted on the shaft 43 and supports the wheel so that its weight will not rest on the driving sprockets 90. As shown in the drawings, the flanged member 47 comprises a sleeve which is rotatably mounted on the shaft 43, intermediate the two driving gears 90. The sleeve is provided with a pair of end flanges 95, which rotatably engage annular recesses 96 formed in the adjacent driving gears. Each flange 95 is provided with a shoulder 97 against which the sides of the adjacent ring 40 of the digging wheel bears.

The arrangement above described is such that the flange supporting member 47 may rotate independently of the driving wheels 90 and thus compensating for the difference in peripheral speeds of the inner periphery of the rings 40 and the peripheral speed of the pitch line of the driving pins 91 of the digging wheel. This construction greatly increases the life of all of the coacting parts, especially that of the driving gear 90 and the teeth 91 of the digging wheel, thus permitting the teeth 91 to be permanently secured to the wheel without reducing the life thereof.

The conveyor mechanism is also driven from the shaft 43. As shown in Fig. 3, a sprocket wheel 100 is drivingly secured to the sprocket 73, heretofore described, and is connected by a driving chain 101 with a sprocket 102 mounted on a stub shaft 103, journalled in a bearing 104 carried by one of the frame members 28 of the supplemental frame 15. The inner end of the shaft 103 is provided with a bevelled gear 105 which meshes with a similar bevelled gear 106 on a cross-shaft 107 journalled in a gear housing 108 carried by the conveyor frame 51.

The housing 108 contains gearing to enable the rotation of the conveyor in either direction, that is, in the direction to move the material to either side of the trencher machine. As shown, a gear 115 is splined to the shaft 107 and is arranged to be moved, either into meshing engagement with a gear 109, on a shaft 110 carried by the housing, or with an idler or reversing gear 111, which is also rotatably mounted in the housing, and which constantly meshes with a gear 112, also secured to the shaft 110. The shaft 110 is provided at its outer end with a sprocket wheel which is connected by a driving chain 113 with a sprocket wheel mounted on a shaft 114 which carries one pair of belt supporting rollers 53.

The shifting of the gear 115 above described, controls the direction of the movement of the belt 52 and thus determines to which side of the machine the dirt is to be ejected. This is accomplished by the movement of the shift lever 60 120. As shown in Fig. 3, the lever 120 is pivotally

connected as at 121 to a bracket 122, mounted on the gear box 108, and is connected by a link 123 with a plunger 124 slidably mounted in the gear box and arranged and adapted to coact with an annular recess 125 formed in the hub of the shiftable gear 115, to shift such gear into engagement with either the gear 109 or the gear 111, as desired. The lever 120 may also be moved to position the shiftable gear 115 to position intermediate the gears 109 and 111 and thus enable the conveyor to be disconnected from the driving mechanism.

From the foregoing description, it will be seen that we have provided an efficient trenching machine having a digging wheel which will be extremely rigid and have provided a wheel support and driving mechanism which minimizes the wear on those parts which rotate with the digging wheel and thus facilitate a simple arrangement of such wheel and at the same time increases the life thereof.

We claim:

1. In a trenching machine, a frame, a digging wheel mounted therein, said wheel including a pair of spaced annular rings, a shaft parallel to the axis of said rings, a member rotatably mounted on said shaft in engagement with the periphery of both rings and provided with radially extending flanges to engage the outer faces of said rings, each ring having a plurality of driving teeth formations secured to its outer face, a pair of gears mounted on said shaft and arranged and adapted to engage said teeth formations, and wherein each of said gears overhang the flanges of said members whereby the teeth of such gears may embrace said rings and are protected by said member from strains set up by said wheel.
2. In a trenching machine, a frame, a digging wheel mounted therein, said wheel including a pair of coaxial spaced annular rings, a shaft mounted on said frame and having its axis parallel to the axis of said rings, a member rotatably mounted on said shaft and having annular portions to engage the periphery of respective rings, said members each being provided with outwardly and radially extending flanges to engage the outer faces of said rings, each ring having a plurality of pins individually secured in a circular path to its outer face, a pair of gears drivingly mounted on said shaft and arranged and adapted to engage said pins to rotate said wheels and wherein the inner face of each of said gears is provided with an annular groove to receive the flanges of said members whereby the teeth of such gears may closely embrace said rings, and are protected by said members against sidewise thrusts or due to inadvertent spreading of said rings.

VINCENT S. PENOTE.
ALBERT R. ASKUE.
